UNITED STATES PATENT OFFICE.

PAUL W. CARROLL, OF DES MOINES, IOWA.

WRINGER DEVICE.

1,392,478.

Specification of Letters Patent. Patented Oct. 4, 1921.

Application filed November 20, 1919. Serial No. 339,455.

To all whom it may concern:

Be it known that I, PAUL W. CARROLL, a citizen of the United States, and a resident of Des Moines, in the county of Polk and State of Iowa, have invented a certain new and useful Wringer Device of which the following is a specification.

The object of my invention is to provide a wringer device, which may be made as part of a wringer used in connection with washing machines or as an attachment thereto, and which is adapted to prevent the tearing of buttons from clothing during the wringing process.

More particularly it is my object to provide in connection, a wringer having rolls with means including endless belts and rollers, so constructed and mounted, as to guide and direct the feeding of clothes to the wringer in such manner that buttons will always be presented edgewise to the wringer rolls, and will therefore never be torn from the garments to which they are fastened.

With these and other objects in view, my invention consists in the construction, arrangement and combination of the various parts of the device, whereby the objects contemplated are attained, as hereinafter more fully set forth, pointed out in my claims and illustrated in the accompanying drawings, in which:

Figure 1 shows a side elevation of a wringer device embodying my invention.

Fig. 2 is a vertical, sectional view through the same.

Fig. 3 shows a side elevation, illustrating the button saving device with the belts removed and the rollers separated.

Fig. 4 shows a perspective view of a modified form of my invention; and

Fig. 5 is a vertical, sectional view through the form of the device illustrated in Fig. 4.

In the accompanying drawings, I have used the reference numeral 10 to indicate generally an ordinary wringer of the type used with domestic washing machines, having the parallel rubber covered rolls 11. Wringers of this type have upright supports at their ends.

In the form of my invention illustrated in Figs. 1, 2 and 3, I have shown arms 12, extending horizontally away from the wringer proper, as illustrated in the drawings, and arranged parallel with each other in sub-

stantially the same horizontal plane. The arms 12 are connected at their ends farthest from the wringer by means of a rotatably mounted roller 13, preferably provided with a plurality of blades 14 having blunt edges, 60 which blades are spaced substantially equal distances from each other circumferentially of the roller.

Spaced above each arm 12 is an arm 15, hinged at one end as at 16 to one of the upper right end members of the wringer.

Springs 17 are employed for tending to draw the arms 15 and 12 at each end of the wringer together.

Between what, I may term, the outer ends of the arms 15 is a rotatably mounted roller 18, similar to the roller 13, and provided with blades 19, similar to the blades 14. Extending around the roller 13 and the lower wringer roll 11, as illustrated in Fig. 2, is an endless belt 20 of canvas or any suitable material, which is mounted in place with sufficient stretch or tension to cause it to travel when the lower wringer roll is rotated.

Extended around the roller 18 and the upper wringer roll is a similar endless belt 21.

In Figs. 4 and 5, I have shown a modified form of my invention in which the structure already described with the exception of 85 the belts, is duplicated on the opposite side of the wringer, the various parts being indicated by the reference numerals already given to their similar parts with addition of the reference character "a." Thus the arms 90 are indicated with the characters 12^a and 15^a and so on.

In the case of the form of invention shown in Figs. 4 and 5, I have shown extending over the two rollers 13^a, an endless belt 20^a, 95 which receives the lower wringer roll between its upper and lower stretches. Extended over the rollers 18^a is a similar belt 21^a, which receives between its upper and lower stretches, the upper wringer roll.

In the practical use of my improved device, the clothes are fed between the rollers 18 and 13 or between the rollers 18^a and 13^a, as the case may be, and the buttons will be always pressed to position in a plane parallel with the planes of the surfaces of the endless belts, and will be fed to the wringer rolls in such position, so that the buttons will never be torn off.

It will be seen that what may be called 13

the outer ends of the belts have considerable up and down play between the blades on the rollers, so that the buttons will always be moved into proper position for feeding to the wringer rolls.

It may be mentioned that the blades at each upper roller are staggered with relation to the blades of the respective lower roller in the operation of the machine and 10 will always tend to remain staggered.

It is well-known that a common complaint against the ordinary wringers of the type herein considered arises from the fact that a great many buttons are torn from clothing 15 in the use of such wringers. I therefore believe that I have made a very substantial advance in the art, by providing a mechanism for feeding the buttons edgewise to the wringer rolls and thereby preventing the 20 tearing off of the buttons.

It will be noted that my device does not in any way interfere with the ordinary operation of the wringer, and the parts which I add to the wringer to accomplish my purpose 25 are of simple and inexpensive construction and can be furnished with the wringer or may be used as an attachment.

Some changes may be made in the construction and arrangement of the various 30 parts of my device without departing from the essential features and purposes of my invention, and it is my intention to cover by my claims any modified forms of structure or use of mechanical equivalents, which

may be reasonably included within their scope.

I claim as my invention:

1. The combination of a wringer having rolls with a pair of rollers spaced from said rolls, endless flexible members designed to 40 extend around the respective rolls and rollers, and means formed on said rollers for alternately moving the adjacent stretches of the endless members toward and from the rollers as they pass over said means, said 45 means including members staggered relative to each other.

2. The combination of a wringer having rolls with a pair of endless belts extended over said rolls, means for supporting the 50 outer ends of the stretches of said belts at points spaced from the wringer rolls and for holding said belts with stretches thereof adjacent to each other, said means including rollers having blades staggered with relation to each other on respective rollers, and 55 means tending to draw said rollers toward each other.

3. The combination of a wringer, having rolls, a pair of rollers, means for supporting 60 said rollers for permitting their yielding movement toward and from each other, and a pair of endless belts, said belts being extended over the respective rollers and over the respective rolls on the wringer, said 65 rollers having staggered blades.

Des Moines, Iowa, October 27, 1919.

PAUL W. CARROLL.
